Attorney,

UNITED STATES PATENT OFFICE.

GEORGE H. TUTTLE, OF WARREN, OHIO, ASSIGNOR TO THE PACKARD ELECTRIC COMPANY, OF WARREN, OHIO, A CORPORATION OF OHIO.

TRANSFORMER.

Application filed September 8, 1924. Serial No. 736,438.

This invention relates to tap-changing switches, especially adapted for use in connection with transformers, although the invention is, obviously, adapted for other applications.

It is one of the objects of the invention to provide a tap-changing switch mechanism that will be operable from the exterior of the casing in which the mechanism is arranged and thereby avoid opening the casing which, in the case of a transformer, is especially desirable because it avoids the possibility of the entrance of moisture into the transformer and the possibility of dropping tools into the transformer.

A further object of the invention is to provide a tap-changing mechanism, of the kind referred to, in which the switch contacts are of improved construction that will positively clamp the switch blade or connector without depending upon the inherent flexibility of the metal of which the contacts are made, it being the usual practice to make such contacts of copper or other relatively soft material. A further object of the invention is to provide an improved form of switch contact that will have a relatively large area of contact with the switch blade or connector and in which the connector is provided with an actuating rod that extends to the exterior of the casing and carries a handle having a swivel connection therewith so that it will not be possible to damage the switch mechanism by turning or twisting the handle.

A further object of the invention is to provide an improved system of connections between the switch contacts and the taps, which extend to the transformer windings, that will permit a greater number of ratio changes, with a given number of taps, than has been possible with switch mechanisms heretofore used.

Other objects of the invention and the features of novelty will be apparent from the following description taken in connection with the accompanying drawings, of which:—

Figure 1 is an elevation of switch mechanism embodying my invention, shown in

connection with a transformer casing, a portion of which appears in section;

Fig. 2 is a plan view of the apparatus illustrated in Fig. 1;

Fig. 3 is a transverse section on the line 3—3 of Fig. 1;

Fig. 4 is a transverse section on the line 4—4 of Fig. 1;

Fig. 5 is an enlarged side elevation of one of the switches, with parts shown in section;

Fig. 6 is an enlarged longitudinal section of one form of my improved handle for the switch actuating rod;

Fig. 7 is a similar view of another form of handle; and

Fig. 8 is a diagram illustrating my improved system of connecting the switch contacts with the transformer taps.

Referring to the drawings, 10 indicates a fragment of an ordinary weather-proof transformer casing having a manhole 11 provided with a cover 12 which, according to the usual custom, is bolted to the transformer casing and makes a weather-tight joint therewith in any suitable manner as by means of a gasket 13.

The cover 12 carries several tubes 14 which extend above and below the same and which are preferably brazed or welded thereto so as to be rigidly and permanently secured to the cover by weather-proof connections. In the drawings, I have shown five of the tubes 14, arranged in a circle about the center of the cover and extending into the interior of the casing 10 a sufficient distance to permit the switch panels 15 to be secured thereto. For simplicity and ease and cheapness of manufacture I provide separate panels 15 for each of the switches and each of these panels is secured to the lower end of one of the tubes 14 by being clamped thereto by U-bolts 16, as will be readily understood from Fig. 1.

Within each of the tubes 14 there is slidably arranged a switch actuating rod comprising a section 17, of hickory or other suitable insulating material, and an upper section 18 of brass or other non-corrosive metal (see Figs. 6 and 7). The upper end of each of the tubes 14 is provided with

external screw threads 19 and carries a gland 20 for compressing a suitable packing 21 against the surface of the section 18 of the switch actuating rod to prevent the entrance of moisture through the interior of the tubes 14. The sections 17 and 18 of the switch actuating rods are telescoped and secured together by rivets 22 or in any other suitable manner. The lower end of each of the insulating sections 17 of said rods carries a ferrule 23 which is telescoped therewith and secured thereto by rivets 24. Each of these ferrules 23 has a flattened side at its lower end, as indicated at 25 in Fig. 1 and a switch blade or connector 26 is secured to the ferrule 23 by being riveted or otherwise secured on the flattened surface 25.

Each of the panels 15 carries a pair of contacts, at its lower end, suitably spaced apart and adapted to receive the blade or connector 26. The upper contacts of the five switches illustrated are designated generally by the reference letters A, B, C, D and E, respectively. The lower contacts of these five switches are indicated generally by the reference letters F, G, H, J and K, respectively. Each of these contacts comprises a pair of superposed bars 27 and 28 which are supported on the respective panels 15 by two bolts 29, the heads of which engage the outer surface of the bar 28. The opposite end of each of the bolts 29 carries a nut 30 and washer 31 and between the washer 31 and the panel 15 there is a spring 32, which tends to draw the bar 28 toward the bar 27. The panels 15 are preferably provided with sockets 33 to receive the springs 32, as will be most clearly seen from Fig. 4. Washers 34 are provided on the bolts 29 between the bars 27 and 28 for the purpose of providing a definite spacing for the bars when the connector 26 is out of contact therewith. The connector 26 is preferably of rectangular cross-section and, therefore, not rotatable in the contact and the thickness of the connector should exceed that of the washers 34 so that when the connector is forced between the bars 27 and 28 the latter will be separated to a slight extent and thereby made to more firmly clamp the connector between them and provide a good electrical contact.

The upper end of each of the switch actuating rods carries a handle and, in view of the fact that the connector 26 is non-rotatable, I provide handles having swivel connections with the switch actuating rods and thereby avoid the possibility of intentional or accidental damage to the switches or their actuating rods by twisting the latter as such twisting of the rods might break the section 17 or the connections between this section and the upper section 18 or the ferrule 23. In Fig. 6 the handle consists of a tubular member 35 of sufficient internal

diameter to slide over the gland 20 and having a socket 36 at its upper end adapted to receive the upper end of the rod section 18. The latter is provided with an annular groove 37 and pins 38 extend through the member 35 and engage with the groove 37, thereby securing the section 18 and the member 35 together so that the rod may be actuated by the handle member, but providing a swivel connection between the two which permits the member 35 to be rotated relatively to the section 18. The lower end of the member 35 is provided with external screw threads 39 to receive the cap 40, the end of which has an opening to receive the tube 14 and permit the cap 40 to slide on this tube.

In the handle construction illustrated in Fig. 7 a tubular member 41 has an inturned flange 42 at its lower end to form a sliding connection with the tube 14. The upper end of the rod section 18 is provided with a head 43 which loosely engages with the upper end of the member 41 and the upper part of the latter is provided with the external threads 44 to receive the cap 45 which has a suitable internal recess to receive the head 43, without clamping the latter, so that the member 41 may freely rotate relative to the rod section 18.

As will be clearly seen from Figs. 6 and 7 the handles which have been described are so connected with the switch actuating rods as to be capable of moving the latter axially, the outward movement being, in each case, limited by the engagement of the handle with the lower edge of the gland 20, the latter thus acting as a stop.

In Fig. 1 I have illustrated one of the switches with the connector 26 in the lower position in which it connects the contacts E and K, the other switches being in the raised position so as not to connect their respective contacts. In order to insure that but one of the switches may be in the lower or "closed" position, and to lock the remaining switches in the upper or "open" position, I provide a locking device which consists of a rotatable disc 46 which is mounted on an upwardly projecting boss 47 on the cover 12 and which is provided with an upwardly projecting handle 48 by means of which it may be turned. The disc 46 is notched at one side, as indicated at 49, and when this notch is opposite any particular switch actuating rod this rod may be raised or lowered at will but the remaining rods will be locked in their upper position by the engagement of the disc 46 with the lower end of the handles, as will be clearly understood from Fig. 2. When it is desired to close any particular switch all of the switches must be in the "open" position which permits the disc 46 to be rotated for the purpose of aligning the notch 47 with the particular handle of the switch 130.

that is to be closed thereby permitting the actuating rod of that switch to be depressed and, at the same time, locking all of the others.

5 Reference to Fig. 8 will disclose my improved system for connecting the transformer taps to the several switch contacts in order to give the maximum number of ratio changes with the number of taps provided, 10 in this case six. It is customary to provide transformers with multiple-coil windings and to connect these windings through the tap-changing switches so that varying numbers of the turns of the windings may be 15 cut in or out. As shown in Fig. 4 the bar 27 of the switch K extends across to and also constitutes the corresponding bar of the switch F. In like manner the contacts B and C, D and E and H and J are connected 20 together. In addition to forming electrical connection between adjoining contacts the arrangement of the bar 27 provides a brace for the lower ends of the panels carrying the contacts F and K. In like manner the bars 25 which are common to the contacts H and J, B and C and D and E, serve to brace the lower ends of the panels 15. Since the bars which connect the upper series of contacts are in staggered relation with the bars connecting the lower series of contacts, all of the panels 15 are thoroughly braced and securely held in proper relation to the tubes 14.

In Fig. 8 I have indicated at 50 and 51 two 30 coils of one of the windings of a transformer with the taps 52, 53 and 54 extending from the coil 50 and the taps 55, 56 and 57 extending from the coil 51. As shown the tap 52 is connected with the contacts B and C, the tap 53 is connected with the contacts D and E, and the tap 54 with the contact A. The tap 55 connects with the contact G, the tap 56 with the contacts H and J, and the tap 57 with the contacts F and K. The various switch blades or connectors are also 40 shown in Fig. 8 and it will be evident, by following the connections, that when the contacts B and G are connected together all of the turns of the coils 50 and 51 will be 50 in circuit. When the contacts C and H are connected, all of the turns of the coil 50 will be in circuit but a portion of the turns of the coil 51 will be cut out. Following the diagram through it will be clear that various 55 combinations of turns may be provided by the system of connections illustrated and the maximum number of ratio changes may be made for the number of taps shown.

While I have illustrated and described the 60 principles of my invention and what I now consider to be the preferred means for carrying the same into effect, it will be understood that changes may be made without departing from the spirit of the invention, 65 as defined in the appended claims.

Having thus described my invention what I claim is:

1. In apparatus of the class described, the combination of a weather-proof casing, a tube secured in a wall thereof and projecting inwardly and outwardly therefrom, a panel of insulating material supported within the casing, a pair of contacts on said panel in substantial alignment with said tube, a rod 70 slidable in said tube and comprising a section formed of insulating material and a metallic connector adapted to engage said contacts, said connector being non-rotatable in said contacts, a stuffing box on the outer end of said tube comprising a gland 75 having threaded engagement with the tube and a packing cooperating with said rod to make a weather-tight joint therearound, and a handle having a swivel connection with said rod and said tube and movable axially of the latter to actuate said rod for the purpose of connecting and disconnecting said contacts.

2. In apparatus of the class described, the combination of a weather-proof casing, 90 a tube secured in a wall thereof and projecting inwardly and outwardly therefrom, a panel of insulating material supported within the casing, a pair of contacts on said panel in substantial alignment with said tube, a rod 95 slidable in said tube and comprising a section formed of insulating material and a metallic connector adapted to engage said contacts, said connector being non-rotatable in said contacts, a stuffing box on the outer end of said tube comprising a gland having threaded engagement with the tube and a packing cooperating with said rod to make a weather-tight joint therearound, a handle 100 having a swivel connection with said rod and said tube and movable axially of the latter to actuate said rod for the purpose of connecting and disconnecting said contacts, the outward movement of said handle and rod being limited by engagement of said 105 handle with said gland.

3. In apparatus of the class described, the combination of a plurality of switch panels arranged about a central axis and parallel therewith, supporting means at one end of each of said panels, a pair of switch contacts on each panel spaced apart longitudinally of said axis, a separate connector for each pair of contacts, said contacts each comprising a pair of bars that are pressed together and adapted to receive and clamp the cooperating connector between them, and some of said bars being common to contacts on different panels and serving to tie the panels together in mutually bracing relation.

4. In apparatus of the class described, the combination of a plurality of switch panels arranged about a central axis and parallel therewith, supporting means at one end of each of said panels, a pair of switch contacts

on each panel spaced apart longitudinally of said axis, a separate connector for each pair of contacts, said contacts each comprising a pair of bars that are pressed together and adapted to receive and clamp the cooperating connector between them, and certain of said bars extending from contacts on one

panel to contacts on adjoining contacts so as to be common to a plurality of contacts, and the last mentioned bars serving to tie ¹⁰ all of the panels together in mutually bracing relation.

In testimony whereof I affix my signature.
GEORGE H. TUTTLE.
